UNITED STATES PATENT OFFICE.

WESLEY W. SCHETTLER, OF SPRINGFIELD, OHIO, ASSIGNOR TO THE FOOS GAS ENGINE COMPANY, OF SPRINGFIELD, OHIO, A CORPORATION OF OHIO.

OIL-RESERVOIR FOR INTERNAL-COMBUSTION ENGINES.

1,296,124.

Specification of Letters Patent.

Patented Mar. 4, 1919.

Application filed October 24, 1917. Serial No. 198,247.

To all whom it may concern:

Be it known that I, WESLEY W. SCHETTLER, a citizen of the United States, residing at Springfield, in the county of Clark and 5 State of Ohio, have invented certain new and useful Improvements in Oil-Reservoirs for Internal-Combustion Engines, of which the following is a specification.

This invention relates to improvements in 10 oiling devices for internal combustion engines, it more particularly relates to the arrangement of the oil supply for the engine.

The object of the invention is to provide 15 an oil reservoir so located that the oil will be maintained in a freely flowing condition by the heat of the cooling water.

A further object of the invention is to provide 20 an oil reservoir so located in the water reservoir as to not only furnish an adequate supply of oil but also to act as a deflector for the water during its circulation through the reservoir to prevent the same from splashing out of the supply opening.

In the accompanying drawings:—

25 Figure 1 is a longitudinal section of so much of an internal combustion engine and its water jacket and reservoir as is necessary to illustrate my improvements, my improved oil reservoir being shown applied thereto.

30 Fig. 2 is an enlarged section of a portion of the water reservoir and of the oil reservoir.

Fig. 3 is a front view in detail of the 35 water reservoir showing the oil reservoir in dotted lines.

The engine which I have shown my invention applied to is of the horizontal stationary type, 1 representing the base upon which is mounted the crank case 2, having 40 bearings for the crank shaft 3, which carries the fly wheels 4 (one only being shown in the present case) on the exterior of the casing, the crank shaft being connected in the usual way with the piston rod 5 of the 45 piston 6.

The cylinder 7 is in the present case integral with the crank case and provided with the usual form of integral water jacket 8. The water reservoir which supplies water to 50 the jacket is indicated by 10 and has an opening 9 in its top through which the water is supplied to the same. This water reservoir is in the present case located substantially above the crank case so as to furnish a better balance for the engine, the floor 55

11 of the reservoir separating the same from the interior of the crank case.

My improvement consists in locating in this water reservoir an oil reservoir 12. This oil reservoir is cast integral with the 60 water reservoir and extends across the entire width of the same at the upper forward portion thereof, the rear wall of the oil reservoir being adjacent to and extending downwardly from the water supply opening 65 9. An opening extending into the upper part of the reservoir 12 and closed by a plug 13 is provided for replenishing the reservoir with oil and a suitable valve 14 of well known construction communicating 70 with the lower portion of the oil reservoir is provided for conveying the oil to the parts to be lubricated.

From the construction explained it will be 75 seen that the oil in the oil reservoir will be kept in a heated condition by the water and by its peculiar location it also acts as a deflector for the water to prevent the same from splashing out through the opening 9.

Further, the particular location of the oil 80 reservoir is one where it will be brought into intimate contact with the water which is first heated so that the oil will be quickly brought to a condition to flow freely, the circulation of the water being upwardly 85 along the forward wall of the water reservoir.

Having thus described my invention, I claim:—

1. In an internal combustion engine, the 90 combination, with a cylinder and its water jacket, of a water reservoir communicating with said jacket, and an integrally formed oil reservoir located in said water reservoir.

2. In an internal combustion engine, the 100 combination, with a cylinder and its water jacket, of a water reservoir communicating with said jacket, and an oil reservoir located in said reservoir in the path of the water 105 circulating from said reservoir and in proximity to said jacket.

3. In an internal combustion engine, the 105 combination, with a cylinder and its water jacket, of a water reservoir communicating with said water jacket, and an oil reservoir in said water reservoir formed integrally therewith, said oil reservoir extending across the upper forward portion of said water reservoir.

4. In an internal combustion engine, the combination, with a cylinder and its water jacket, of a water reservoir having an upper supply opening, an oil reservoir located in
5 said water reservoir and formed integrally therewith, said oil reservoir located in the upper forward portion of said water reser-

voir in proximity to said opening to act as a deflector for the water.

In testimony whereof, I have hereunto set 10 my hand this 9th day of October 1917.

WESLEY W. SCHETTLER.
